US00D869201S

(12) United States Design Patent (10) Patent No.: US D869,201 S
Davis et al. (45) Date of Patent: * Dec. 10, 2019

(54) CONSOLE

(71) Applicant: WALKER EDISON FURNITURE COMPANY LLC, Salt Lake City, UT (US)

(72) Inventors: Matthew Davis, Murray, UT (US); Brad Bonham, Draper, UT (US); Richard Packer, Kaysville, UT (US)

(73) Assignee: Walker Edison Furniture Company LLC, Salt Lake City, UT (US)

() Term: 15 Years

(21) Appl. No.: 29/656,486

(22) Filed: Jul. 12, 2018

(51) LOC (12) Cl. 06-04

(52) U.S. Cl.

USPC D6/669

(57) CLAIM

The ornamental design for a console, as shown and described.

DESCRIPTION

FIG. 1 is a front perspective view of a console, showing the first embodiment of our new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right elevation view thereof;

FIG. 7 is a left elevation view thereof;

FIG. 8 is a front perspective view of a console, showing the second embodiment of our new design;

FIG. 9 is a front elevation view thereof;

FIG. 10 is a back elevation view thereof;

FIG. 11 is a top plan view thereof;

FIG. 12 is a bottom plan view thereof;

FIG. 13 is a right elevation view thereof; and,

FIG. 14 is a left elevation view thereof.

The broken lines in the drawings are for the purpose of illustrating portions of the article that form no part of the claimed design.

1 Claim, 8 Drawing Sheets
